UNITED STATES PATENT OFFICE.

WALTER W. SIBSON AND THOMAS ALLSOP, OF PHILADELPHIA, PENNSYLVANIA,
ASSIGNORS TO THE PHILADELPHIA DRYING MACHINERY COMPANY, OF PHILA-
DELPHIA, PENNSYLVANIA, A CORPORATION OF PENNSYLVANIA.

CIRCULATING DYEING-MACHINE.

1,150,306.

Specification of Letters Patent. Patented Aug. 17, 1915.

Original application filed July 14, 1913, Serial No. 778,858. Divided and this application filed November 28, 1914. Serial No. 874,402.

To all whom it may concern:

Be it known that we, WALTER W. SIBSON and THOMAS ALLSOP, of Philadelphia, in the county of Philadelphia and State of Pennsylvania, have jointly invented certain new and useful Improvements in Circulating Dyeing-Machines, whereof the following is a specification, reference being had to the accompanying drawings.

10 The invention relates more particularly to a device for supporting articles to be dyed. An object of the invention is to provide a supporting bar on which the articles may be hung and wherein the surface of the article 15 engaged by the supporting bar is relatively small.

A further object of the invention is to provide a supporting bar of the above type which may be readily detached from its 20 holder so as to facilitate loading the same with skeins of yarn or other articles similarly looped.

In the drawings, Figure I, is a longitudinal sectional view through a dyeing apparatus showing the improved supporting bars therein. Fig. II, is an enlarged sectional view through one of the supporting bars showing in dotted lines an article carried 30 thereby. Fig. III, is a plan view of one of the bars.

The invention consists generally in forming a supporting bar from metal which is bent into V shape and mounted on a frame so that said V will be upright. The bar is 35 provided with perforations to permit the dye liquor to circulate through the bar.

Referring more in detail to the drawings, I, is a receptacle or vat which is preferably 40 rectangular in horizontal section and has side walls and end walls. This receptacle is divided by a partition 2, so as to provide a main dye chamber 3, and a circulating chamber 4. The partition 2, terminates short of the bottom of the receptacle so as to 45 form a passage for the dye liquor underneath the same. The partition likewise terminates short of the top of the receptacle so as to form a passage above the top of the partition for the dye liquor. Located in the circulating chamber 4, is a propeller 5, which is driven by any suitable means. Valves 6, and 7, control the direction of flow of the dye liquor.

This apparatus is shown and described and claimed in detail in our co-pending 55 application Serial No. 778,858, filed July 14th, 1913, of which this application is a division.

The articles to be dyed are supported in the main dye chamber 3, by a supporting device consisting of a perforated plate 8, forming a holder which is carried by brackets 9, 9, bolted to a cover 10. The cover 10, is adapted to rest upon the side walls of the receptacle and is held clamped 60 thereto by swinging clamps 11, which are adapted to engage pins 12, carried by the side walls of the receptacle as clearly shown in dotted lines in Fig. I. The cover is also provided with spaced lifting eyes 15. 70

The supporting plate or holder 8, is bent downwardly at its sides and ends as indicated at 14, and 15, respectively. The supporting bars 16, are carried by the side members 14, of the perforated plate 8. These 75 bars as clearly shown in the drawings are V-shaped in cross section. The two side members 17, and 18, of said V-shaped bar meet at their lower edges so that the V is upright. The article indicated in dotted 80 lines at A, Fig. II, when hung on the supporting bar will engage only the upper edges of the side members 17, and 18. Said bar is perforated as at 19. The dye liquor in circulating passes through the perforations 19, and will, therefore, freely engage 85 the section of the article spanned between the upper edges of the said members 17, and 18. By this construction of the supporting bar the articles are so held that only a very 90 small portion thereof is covered or engaged by said supporting bar.

The supporting bars are detachably carried by the supporting table, so that they may be readily removed therefrom to 95 facilitate loading with skeins of yarn or the like. When the holder is lifted by the cover, the bars together with the supported articles which are to be dyed, are bodily lifted either into or out of the main 100 dye chamber. The perforations in the plate 8, permit free circulation of the dye liquor therethrough.

While we have shown and described our 105 supporting bar as V-shaped in cross section, it will be understood that the cross section

or shape thereof may be modified so long as only the side edges of the bar serve as the supporting contact with the article to be dyed.

5 It is obvious that minor changes in the details of construction may be made without departing from the spirit of the invention as set forth in the appended claims.

Having thus described our invention, we 10 claim:

1. A circulating dyeing apparatus including in combination a receptacle and means for supporting the articles to be dyed including a bar, so disposed that the edges 15 only contact with the article supported thereon, said bar having perforations extending therethrough between its side edges.

2. A circulating dyeing apparatus including in combination a receptacle and means 20 for supporting the articles to be dyed including V-shaped bars so disposed that the edges only of the bars make contact with the articles supported thereon.

3. A dyeing machine including in combination a receptacle having a main dye chamber, means for causing a uniform flow 25 of dye liquor through said chamber, means for supporting articles to be dyed including a perforated supporting plate, a plurality of V-shaped bars carried by said supporting plate and arranged side by side, the side walls of said bars diverging outwardly and upwardly, whereby the upper edges of said side walls serve as the sole 30 supporting contact for the articles to be dyed.

4. A dyeing machine including in combination a receptacle having a main dye chamber, means for causing a uniform flow of 40 dye liquor through said chamber, means for supporting articles to be dyed including a perforated supporting plate, a plurality of V-shaped bars carried by said supporting plate and arranged side by side, the side walls of said bars diverging outwardly and upwardly, whereby the upper edges of said 45 side walls serve as the sole supporting contact for the articles to be dyed, each of said

bars having perforations formed therethrough to permit the dye liquor to pass 50 through the bar.

5. A dyeing apparatus including in combination a receptacle having a main dyeing chamber, a cover therefor, brackets depending from said cover, a perforated plate carried by said brackets, said plate having downwardly extending side and end walls and supporting bars carried by the side walls, said supporting bars being V-shaped 55 in cross section, and arranged side by side with the said walls thereof diverging outwardly and upwardly whereby the article to be supported makes contact only with the outer edges of said side walls, said bars being perforated to permit the dye liquor to 60 pass therethrough.

6. A supporting bar for a dyeing apparatus comprising a metal strip bent longitudinally between its side edges and means 70 for supporting said bar with said side edges uppermost, whereby the article to be supported makes contact only with said side edges, said bar being perforated at points between its side edges.

7. In a dyeing apparatus the combination 75 of a perforated plate having the sides thereof bent downwardly and provided with V-shaped openings and sheet metal bars bent longitudinally so as to fit said V-shaped openings, said openings being so disposed 80 that the side walls of said bars diverge outwardly and upwardly whereby the upper edges of said side walls serve as the sole supporting contact for the articles to be dyed, said bars having perforations therein 85 to permit the dye liquor to circulate therethrough.

In testimony whereof, we have hereunto signed our names at Philadelphia, Pennsylvania, this twenty-fifth day of November, 1914.

WALTER W. SIBSON.
THOMAS ALLSOP.
